UNITED STATES PATENT OFFICE.

JAMES M. ROBINETTE, OF WILLIAMSON, WEST VIRGINIA.

GAME-CUE.

1,152,908.

Specification of Letters Patent.

Patented Sept. 7, 1915.

Application filed October 29, 1913. Serial No. 797,965.

To all whom it may concern:

Be it known that I, JAMES M. ROBINETTE, citizen of the United States, residing at Williamson, in the county of Mingo and State 5 of West Virginia, have invented certain new and useful Improvements in Game-Cues; and I do hereby declare the following to be a full, clear, and exact description of the invention, such as will enable others 10 skilled in the art to which it appertains to make and use the same.

This invention comprehends improvements in game cues, such as are used in playing pool, billiards, bagatelle, et cetera, and 15 has for one of its objects to provide a spring or mechanical cue of this nature which shall be of extremely simple construction, cheap to manufacture and very practical.

Another and more specific object of the 20 invention is to provide a cue including a butt, a stem, spring means for forcing the butt and stem away from each other, and latch mechanism carried by the butt, whereby the spring means may be thrown into 25 operation when it is desired to make a shot.

The invention also aims to generally improve cues of this nature to render them more useful, practical and commercially desirable.

30 With these and other objects in view as will become more apparent as the description proceeds, the invention consists in certain novel features of construction, combination and arrangement of parts as will 35 be hereinafter more fully described and claimed.

For a complete understanding of my invention, reference is to be had to the following description and accompanying drawings, in which—

Figure 1 is a side elevation of my improved cue, Fig. 2 is a fragmentary longitudinal sectional view, Fig. 3 is a transverse section taken on the plane of line 45 3—3 of Fig. 2, Fig. 4 is a similar view taken on the plane of line 4—4 of Fig. 2, and Fig. 5 is a fragmentary longitudinal sectional view taken on the plane of line 5—5 of Fig. 2.

50 Referring in detail to the drawings by numerals, 5 designates the butt of my improved cue, 6 the stem thereof, and 7 a sleeve being rigidly secured to the butt and surrounding the inner end of the stem. A 55 circular block 8 having a pair of laterally extending arms 9 formed integrally there-

with is secured to the outer end of the butt by the fastening members 10 which extend through said arms and thread into the butt. This block is formed with an axial opening 11 which is rectangular in cross section and with a transverse slot or opening 12 which extends at right angles to the opening 11 and which is also rectangular in cross section. A latch 13 slides through the opening or slot 12 and is formed with an elongated slot 14 which registers with the opening 11 in the block. One end of the latch is extended angularly, as indicated by the numeral 15 and has attached thereto a 70 thumb screw 16, the shank of which passes through an opening 17 in the sleeve 7. A peripheral chamber 18 is formed in the block 8 and is adapted to receive the angular portion 15 of the latch when said portion is 75 formed inwardly, and the butt 5 is formed with a chamber 19 for a similar purpose. A flat metal spring 20 is secured at its outer end to the butt, and has its forward end extended into engagement with the inner 80 side of the portion 15 of the latch, whereby said portion is normally forced outwardly into engagement with the sleeve 7.

A bar 21 is secured at one end to the stem 6 by means of a pin 22, and extends longitudinally through the sleeve 7 and through the opening 11 formed in the block. A pin 23 is carried by the outer end of the bar and prevents said bar becoming disengaged from the block. The butt 5 is formed with a 90 longitudinal recess 24 to receive the outer end of the bar, and a helical spring 25 is coiled about the bar between the stem 6 and block 8. One edge of the bar is formed with a series of notches 26 and a pair of 95 notches 27 and 28, the walls of which are adapted to engage the latch 13.

When it is desired to set the cue, the thumb screw 16 is forced inwardly so as to disengage the latch 13 from the bar 21 and 100 the stem 6 is then forced inwardly, compressing the spring 25 within the sleeve 7. When the desired tension has been placed upon the spring, the pressure is removed from the screw 16, and the spring 20 forces 105 the latch into locking engagement with one of the teeth 26 or the notch 27. After the cue has been properly aimed, it is only necessary to force the screw 16 inwardly so as to disengage the latch from the bar 21 in order 110 that a shot may be made.

From the foregoing description taken in

connection with the accompanying drawings, it will be seen that I have provided a very simple and practical mechanical cue which may be easily operated, and which 5 will make it possible to play a game of pool or billiards with very little exertion.

While I have shown and described the preferred embodiment of my invention, it will be understood that minor changes in 10 construction, combination and arrangement of parts may be made without departing from the scope and spirit of the invention as claimed.

Having thus described my invention, I 15 claim:—

A game cue including a butt having a longitudinal recess formed therein, a block secured to said butt having intersecting axial and diametrical openings, a stem, a bar connected at one end to said stem and projecting at its other end through the axial opening and into the longitudinal recess, said bar being formed upon one edge with a plurality 20

of teeth, a latch slidably mounted in the diametrical opening in the block and formed 25 with a longitudinal slot adapted to be moved into registration with the axial opening to permit sliding movement of the bar therethrough, an angular extension on said latch, a spring disposed between said butt and said 30 angular extension for holding the latch normally in locking engagement with the teeth of said bar, a spring coiled upon the bar and disposed between the stem and the block, and a stop pin secured in the end of the bar 35 slidably in the longitudinal recess adapted to engage the block to limit the outward movement of the bar and stem under the influence of the coiled spring.

In testimony whereof I affix my signature 40 in presence of two witnesses.

JAMES M. ROBINETTE.
